UNITED STATES PATENT OFFICE.

CECIL C. TROXEL, OF NINNEKAH, OKLAHOMA.

SLED-AXLE PLOW ATTACHMENT.

Application filed August 29, 1927. Serial No. 216,194.

The present invention relates to an improved cultivator attachment for a sled or what is more commonly known in the trade as a "go devil".
5 The purpose of the invention is to provide cultivating plows for acting on and properly building the dirt up around the plant after the rotary discs on the sled have preceded and have thrown the dirt out from the plant 10 in the customary manner.

This arrangement is so constructed that the small plows run in the lister furrows for acting on the dirt around the plants after it has been previously acted on by the discs, 15 and it is believed to be advantageous for young plants such as cotton, corn, etc.

The structural details upon which the novelty is based will become more readily apparent from the following detailed 20 description and will be specified in the concluding claim.

In the drawings:—

Figure 1 is a perspective view of the attachment showing the manner in which it is 25 associated with a supporting arch on the rear end of the sled.

Figure 2 is a top plan view of the complete structure.

In the drawings the reference character 30 3 designates the rails of the sled which are provided with clips 4 to which the laterally directed end portions 5 of the arch 6 are fastened through the medium of short plates 7 and complementary fastening bolts 8. The 35 attachment is generally designated by the reference character 9 and is adapted to be fastened upon the supporting arch 6. The attachment comprises the frame which includes a pair of spaced parallel side bars 40 10 having their rear end portions 11 directed downwardly upon the curvature represented in the drawings.

Disposed between the rear end portions of the side bars is a cross bar 12. At the forward end of the side bars we find a pair of substantially U-shaped members 13 and 14 whose laterally directed ends are bolted to the side bars in the manner shown. These members 13 and 14 are spaced apart and are 50 in turn bolted or otherwise fastened to the vertical arm portions of the arch 6. In addition I provide a clamp which is connected with the crown portion of the arch. This clamp is composed of complementary 55 members 15 and 16 which are bolted to the crown as shown. The member 16 is longer

than the member 15 and terminates in an upwardly directed rear end 17 having an opening for passage of the upper end of a rod member 18. The rod member 18 is fastened at its lower end to the cross piece or member 12. Cotter keys are employed for fastening the rod member in place. In addition, a coil spring 19 surrounds the upper end portion of the rod and bears against the 60 clamp member 16. At its lower end the spring bears against an adjustable collar 20 held in place by set screw 21.

The downturned end portion 11 of the side bars are equipped with small plows 22 disposed to travel in the usual lister furrows. These plows are fastened to the side bars by 70 novel means which in both instances is the same. Therefore, a description of the means on one side will suffice for both.

The improved means comprises a pair of substantially L-shaped brackets 23 pivotally connected between their ends to the extremity of the down-turned portion 11. The plow is bolted or otherwise fastened to these 80 members as shown, being connected to the free end portions of the long arms thereof. Pivotally connected to the short arms of these brackets are links 24 which are connected to complementary and longer links 25. 85

The links 25 are connected to the side bars as shown in Figure 1 and the intermediate portions thereof are connected to a head on a horizontal stem 26. This stem extends through a U-shaped guide 27 and a coiled 90 spring 28 surrounds the stem bearing at one end against the guide and at its opposite end against the head. Thus a yieldable shock absorber is provided for the plow.

By considering the detailed description in 95 connection with the drawings a clear understanding of the invention will be had, therefore, a more lengthy description is thought unnecessary.

Minor changes coming within the field 100 of invention claimed may be resorted to if desired.

Having thus described the invention, what I claim as new and desire to secure by Letters Patent is:—

In a structure of the class described, in combination with a supporting arch, a horizontal frame embodying spaced parallel side bars having down turned rear end portions, 105 plows connected to the extremities of the 110 downturned end portions, a cross member between the rear end portions of said side

bars, and a pair of substantially U-shaped cross members having their laterally directed end portions connected with the forward ends of said side bars, said U-shaped members being bolted to the upstanding portions of said arch, together with a clamp fastened to the crown portion of said arch, a rod member fastened to said clamp at its

upper end and to said cross member at its lower end, an adjustable collar on said rod, and a coil spring surrounding said rod and bearing at its upper end against said clamp and at its lower end against said collar. 10

In testimony whereof I affix my signature.

CECIL O. TROXEL.
